UNITED STATES PATENT OFFICE.

JOHN WILLIAMS AND JUDSON WILLIAMS, OF PHILADELPHIA, PENNSYLVANIA.

PISTON.

Application filed December 11, 1924. Serial No. 755,247.

To all whom it may concern:

Be it known that we, JOHN WILLIAMS and JUDSON WILLIAMS, citizens of the United States, residing at Philadelphia, in the county of Philadelphia and State of Pennsylvania, have invented certain new and useful Improvements in Pistons, of which the following is a specification.

This invention relates to an improved engine piston and seeks, among other objects, to provide a piston wherein, in use, looseness of the piston will, to all intents and purposes, be permanently overcome.

The invention seeks, as a further object, to provide a piston wherein so-called piston slap will be eliminated and the usual troubles resulting therefrom thus overcome.

And the invention seeks, as a still further object, to provide an over-size self-conforming piston which will take up wear as wear occurs while undue friction will be avoided.

Other and incidental objects will appear hereinafter.

In the accompanying drawings:

Figure 1 is a vertical sectional view on the line 1—1 of Figure 2, looking in the direction indicated by the arrows, a cylinder being shown in dotted lines.

Figure 2 is a vertical sectional view on the line 2—2 of Figure 1, looking in the direction indicated by the arrows, this view illustrating the piston in position within a conventional cylinder.

Figure 3 is a horizontal sectional view on the line 3—3 of Figure 2, looking in the direction indicated by the arrows.

In accordance with the present invention, the improved piston is formed with a head 10 which is provided internally with reinforcing ribs 11 and externally with an approved number of ring grooves 12 to receive expandable rings 13 in the usual manner. The rings are conventionally shown. Depending from the head is a cylindrical skirt 14 integral with the head and formed in the skirt at the base of the head are oppositely disposed segmental slots 15 defining intervening webs 16 therebetween. At said webs, the skirt is formed with parallel side plates 17 which extend in chordal relation to the circumference of the skirt, being free at their lower edges, and formed on said plates are oppositely disposed wrist pin bearings 18 braced by reinforcing webs 19. Formed in the skirt at one side thereof is a diagonal slot 20 which is normally of uniform width

and opens at its lower end through the lower edge of the skirt while at its upper end, the slot opens into one of the grooves 15. The skirt is thus severed throughout its length 60 and it is now to be observed that the metal from which the piston is formed is resilient so that the skirt is thus adapted to flex. In other words, the skirt may be contracted in circumference and thus brought under tension, when the skirt will tend to expand to its normal diameter. Any approved metal or alloy may be employed in forming the piston, provided the necessary resiliency is present. Formed in the skirt 14 near its 70 lower end is an external annular oil groove 21.

In Figure 1 of the drawings, we have shown a conventional cylinder in dotted lines at 22, and attention is now directed to the 75 fact that the skirt 14 of the piston is tapered from an external over-size diameter at the lower end of the skirt to substantially cylinder size diameter at the upper end of the skirt so that the piston is thus of truncated 80 cone-shape. The point is stressed that the flare of the skirt is over cylinder size as distinguished from under cylinder size. In practice, the piston is first formed in the 85 rough, when the skirt is turned or ground externally to impart the desired taper thereto. The taper may start at a few thousandths of an inch over cylinder size at the lower end of the skirt and stop at substantially cylinder size at the level of the lower edges of the 90 slots 15, or, as has been found expedient in some cases, the taper may stop at substantially cylinder size at a level close below said slots. In any event, the skirt is externally 95 tapered at its lower end portion and the flare thus imparted to the skirt is over cylinder size. In Figure 1 of the drawings, the flare is exaggerated to more clearly bring out the feature.

In Figures 2 and 3 of the drawings, we 100 have shown the piston disposed within a conventional cylinder 23 and, as will be observed, the lower end portion of the skirt 14 of the piston is held contracted by the cylinder wall. In this connection, it is to be 105 recalled that the upper end of the skirt is substantially cylinder size. Furthermore, the upper end of the skirt is reinforced by the webs 16 so that the contraction of the skirt at its upper end is not appreciable. 110 However, as the lower end of the skirt is approached, the contraction of the skirt

- gradually increases in proportion to the flare of the skirt and accordingly, the pressure of the skirt against the wall of the cylinder gradually increases from the upper 5 end of the skirt to the lower end thereof. A tight fit between the piston and cylinder is thus effected and as the wall of the cylinder and the skirt of the piston wear, the skirt will, of course, expand to take up such 10 wear so that the tight fit between the piston and cylinder will be maintained. In this connection, it is to be noted that a piston having a straight split skirt over cylinder size would not accomplish the objects of 15 the invention for the reason that such a skirt, when contracted to cylinder size at its upper end, by the insertion of the piston in a cylinder, would be flexed to under cylinder size at its lower end. This is due to 20 the fact that the skirt is necessarily reinforced and braced at its upper end by the piston head while the lower end of the skirt is free. Accordingly, a pressure at the top of the skirt sufficient to contract a straight 25 skirt to cylinder size, would cause an over flexing of the lower end of the skirt. This result is avoided in the present invention, by tapering the skirt exteriorly toward its upper end so that the over size lower end 30 portion of the skirt is pressed against the wall of the cylinder with a force maximum at the lower end of the skirt and gradually decreasing toward the upper end of the skirt. 35 When the piston is newly installed, the piston will move rather stiffly in the cylinder. However, it has been discovered that the heat of the combustion at the upper end of the piston will heat-treat the piston so

that after the piston is worn in, as it is commonly called, the piston becomes accommodated to the exact shape of the inner surface of the cylinder with the result that the piston will then travel smoothly within the cylinder. However, no looseness is developed and the piston still expands to provide a tight joint with the cylinder wall. Furthermore, it has been discovered that when the improved piston is installed in an old cylinder which has become more or less worn, the piston will, after a short period of use conform to the shape of the worn cylinder and form a tight joint therewith throughout the inner circumference of the cylinder. We thus provide a piston which will eliminate the various troubles now experienced from loose or worn pistons. 40 45 50 55

Having thus described the invention, what we claim is:

A piston comprising a head having a resilient skirt provided with wrist pin bosses and being disconnected from the head between said bosses, the skirt being provided with a split extending from the lower end of the skirt above the plane of the axes of 60 said bosses and being externally tapered from an over cylinder size diameter at its lower end toward its upper end whereby when the piston is inserted in a cylinder and the skirt is compressed by the cylinder wall 65 70 the external surface of the skirt will bear against the cylinder wall substantially uniformly.

In testimony whereof we affix our signatures.

JOHN WILLIAMS.
JUDSON WILLIAMS.
